DES. 2204

Elmer J. Mey, of Lowell, Mass.
Assign to

The Lowell Manufacturing Company, of the same place.

Letters Patent No. 2204 Dated Oct 17-1865.

Design for a Carpet Pattern.

The schedule referred to in these letters Patent and making part of the same.

To all whom it may concern:

Be it known that Elmer J. Mey, of Lowell, in the County of Middlesex and State of Massachusetts, have originated and designed a new Pattern for Carpets or other fabrics, of which the following is a full, clear and exact description, reference being had to the accompanying drawings, making part of this specification.

This design is a combination of Gothic and Persian Style, the particular form being shown in the accompanying photographic drawing forming a part of this specification.

The colors employed for the different portions of the design, may be varied to suit the taste and wish of the manufacturer.

Claim.

What I claim as my invention and desire to secure by Letters Patent is,

The Design or Pattern for Carpets or other fabrics herein set forth.
